NECKTIE ATTACHMENT

Hyrame D. Halsey, Cambridge City, Ind.

Application July 5, 1949, Serial No. 103,135

5 Claims. (Cl. 2—153)

1

This invention relates to new and useful improvements and structural refinements in necktie attachments, and the principal object of the invention is to simulate the appearance of a knot in a four-in-hand necktie, without the conventional necessity of actually tying the knot or otherwise twisting the tie.

This object is achieved by the provision of the instant attachment assuming the form of an inverted, substantially frusto-conical shell which is adapted to have the necktie threaded therethrough in such manner that the shell is exposed and simulates the appearance of the usual knot.

One of the features of the invention, therefore, resides in the specific structural arrangement of the shell, while another feature resides in the provision of means in the shell for guiding the necktie and for forming depressions or short grooves in the portion of the tie immediately under the shell so as to further simulate the realism of an actually knotted tie.

Some of the advantages of the invention lie in its simplicity of construction, in its pleasing appearance, in its adaptability to convenient installation and removal, and in its adaptability to economical manufacture.

With the above more important objects and features in view and such other objects and features as may become apparent as this specification proceeds, the invention consists essentially in the construction and arrangement of parts as shown in the accompanying drawings, in which:

Figure 1 is a perspective view of a necktie showing the invention in situ thereon;

Figure 2 is a fragmentary rear perspective view of the subject shown in Fig. 1;

Figure 3 is a cross-sectional detail, taken substantially in the plane of the line 3—3 in Figure 1, but with the necktie removed;

Figure 4 is a cross-sectional detail, taken substantially in the plane of the line 4—4 in Figure 3;

Figure 5 is a vertical cross-sectional view of the invention applied to a collar button;

Figure 6 is a plan view of a specially constructed tie such as may be used with the invention;

Figure 7 is a fragmentary front perspective view, similar to that shown in Figure 1, but illustrating a modified embodiment of the invention;

Figure 8 is a cross-sectional view, taken substantially in the plane of the line 8—8 in Figure 7;

Figure 9 is a fragmentary front perspective view of a further modified embodiment of the invention;

2

Figure 10 is a cross-sectional view, taken substantially in the plane of the line 10—10 in Figure 9; and

Figure 11 is a cross-sectional view, taken substantially in the plane of the line 11—11 in Figure 10.

Like characters of reference are employed to designate like parts in the specification and throughout the several views.

Referring now to the accompanying drawings in detail, more particularly to Figures 1—5 thereof, the reference character 10 designates a conventional necktie to which has been applied the invention in the form of an attachment designated generally by the reference character 12, so as to simulate the appearance of a tied knot without actually involving tying or knotting of the tie.

The attachment 12 consists of an inverted, substantially frusto-conical shell 14 which is preferably formed from a single piece of material and is slightly flattened so as to provide an arcuate front wall 16 and a pair of convergent back walls 18, as is best shown in Figure 3.

It is to be noted that the shell 14 has open upper and lower ends and the outer surface thereof is preferably covered with suitable fabric material 20 which may or may not be the same as the material of the tie with which the invention is to be used.

The material 20 may be secured to the outer surface of the shell 14 in any desired manner, such as for example, by adhesive, and the upper and lower edges of the material are preferably turned over inwardly on the corresponding upper and lower edges of the shell 14, as indicated at 22.

What may be referred to as a necktie guiding and forming member designated generally by the reference character 24 is positioned in the shell 14 and consists of a single length of resilient wire which is angulated so as to provide a pair of spaced, juxtaposed, intermediate portions 26 which extend longitudinally of the shell in spaced relation to the front wall 16. The lower end portions of the wire from which the member 24 is formed are angulated inwardly so as to provide a pair of spaced forming elements 28 in the lower end portion of the shell 14, and a connecting portion 30 which extends between the elements 28 and is secured to the inner surface of the front wall 16, substantially as shown.

The upper end portions of the wire from which the member 24 is formed are angulated inwardly from the front wall 16 so as to provide a pair of spaced, juxtaposed and substantially triangular

guiding elements 32, the diagonal portions 34 of which, in turn, coact with the inner surface of the front wall 16 in defining a pair of spaced tie guiding passages 36 in the upper end portion of the shell 14.

When the invention is placed in use, the tie 10 is simply doubled upon itself and the doubled portion thereof is passed upwardly through the lower end of the shell 14 and after emerging from the upper end, the doubled portion is spread apart and each side placed in one of the passages 36. The portion of the tie in the shell is disposed between the elements 28 and the rear wall 18 of the shell, so that the entire attachment is frictionally retained in proper position on the tie by the elements 28. Moreover, the frictional engagement of these elements with the tie will result in the formation of short grooves or elongated depressions in the tie, as indicated at 38 in Figure 1, thus simulating the effect of actually tying a knot in the tie. Needless to say, the configuration of the shell 14 is such as to simulate the appearance of an actually tied knot, this being effected without the conventional necessity of knotting or otherwise mutilating the tie itself.

In applying the tie and the attachment to the collar of a shirt, the invention may be simply disposed between the collar wings, or alternatively, the collar button 40 may be inserted between the juxtaposed elements 32 as shown in Figure 5, wherein the reference character 42 designates the shirt front, 44 the collar, and 46 one of the collar wings.

It may be explained at this point that when the tie is applied to the attachment as already described, it is preferable to twist the portions of the tie in the shell so that they are superimposed, and if a conventional tie is used, it will be found that under such circumstances the narrow end of the tie will lie in a reverse position (see 48 in Figure 1) under the wide end 50, which actually is not a detriment, since the reversed narrow end portion is hidden under the wide end portion, as shown. However, if it is desired to avoid reversal of the narrow end portion of the tie, a special tie may be used, as indicated at 52 in Figure 6, wherein the wide end portion 54 of the tie is constructed in the conventional manner with the seam 56 on the reverse side, while the narrow end portion 58 has its seam 60 on the front side, the two halves of the tie being secured together by a transverse seam 62. It will be apparent that when this special tie is applied to the attachment, the seam on both end portions of the tie will be disposed on the reverse side.

Referring now to the accompanying Figures 7 and 8, these illustrate a modified embodiment of the invention designated generally by the reference character 70, the same being similar to the embodiment 12 insofar that it embodies in its construction an inverted, substantially frust-conical shell 72 provided with fabric covering 74 and equipped in the interior thereof with a necktie guiding and forming member 76.

The member 76 is similar to the member 24, with the exception that the lower end portion of the rod from which the member 76 is angulated so as to provide a substantially triangular or V-shaped protuberance 78 which extends inwardly from the front wall of the shell and is, of course, adapted to frictionally engage the necktie.

It is to be noted that while the aforementioned elements 28 produce or result in the formation of two spaced grooves in the necktie, as shown at 38 in Figure 1, the single, V-shaped element 78

results in the formation of only one groove, as indicated at 80 in Figure 7.

Finally, referring to the further modified embodiment of the invention, illustrated in the accompanying Figures 9-11 and designated generally by the reference character 90, the shell 92 of this embodiment is similar to the shells in the embodiments 12 and 70, but the necktie-forming member 94 consists of spaced, juxtaposed, intermediate rod portions 96 which are connected together at their upper end by a transverse portion 98 secured to the upper end of the shell, so that the guiding elements 32 provided in the embodiments 12, 70 are not present in the embodiment 90.

Moreover, the lower portions of the rods 96 are angulated forwardly to provide a pair of spaced tie-forming elements 100, similar to the aforementioned elements 28, while a pair of U-shaped, juxtaposed rod portions 102 are disposed between the elements 100 and have contiguous side portions affording an additional forming element 104, so that when the attachment is applied to the tie, the elements 100, 104 result in the formation of three spaced depressions in the tie, as indicated at 106 in Figure 9.

It is believed that the advantages and use of the invention will be clearly apparent from the foregoing disclosure and, accordingly, further description thereof at this point is deemed unnecessary.

Having described the invention, what is claimed as new is:

1. A necktie attachment comprising a tapered shell having a large open upper end and a smaller open lower end, said shell including an arcuate front wall and a pair of converging back walls, a necktie guiding and forming member vertically disposed in said shell, said guiding and forming member including a pair of spaced, resilient arms extending vertically within said shell adjacent the inner surface of the arcuate front wall, the upper ends of said arms terminating adjacent the open upper end of said shell and the lower ends of said arms terminating adjacent the open lower end of said shell, a web connecting said arms at their lower ends, means securing the lower portion of said arms to the inner surface of said arcuate front wall, the upper ends of said arms terminating in tie guiding extensions, said guiding extensions extending transversely of the longitudinal axis of said arms and being spaced from the arcuate front wall of the shell to provide necktie guiding passages between the guiding extensions and the shell, and a portion of said guiding and forming member adjacent the lower end thereof projecting into the central portion of the open lower end of said shell to provide a tie forming projection.

2. A necktie attachment comprising a tapered shell having a large open upper end and a smaller open lower end, said shell including an arcuate front wall and a pair of converging back walls, a necktie guiding and forming member vertically disposed in said shell, said guiding and forming member including a pair of spaced, resilient arms extending vertically within said shell adjacent the inner surface of the arcuate front wall, the upper ends of said arms being perpendicular to the longitudinal axis of said arms, and including first sections extending toward each other, second sections extending from said first sections and being parallel and spaced from one another to 75 form a collar button fastener receiving channel

therebetween and third sections diverging from said second sections, each third section terminating at the junction of its related first and second section, said third sections being spaced from the arcuate front wall of the shell and forming guiding extensions to provide necktie guiding passages between the guiding extensions and the shell, the lower ends of said arms terminating adjacent the open lower end of said shell, a web connecting said arms at their lower ends, means securing the lower portion of said arms to the inner surface of said arcuate front wall, and a portion of said guiding member adjacent the lower end thereof projecting into the central portion of the open lower end of said shell to provide a tie forming portion.

3. A necktie attachment comprising a multi-sided shell having a front wall and open upper and lower ends, a pair of spaced elongated support wires vertically disposed in said shell and each having one end secured to the lower end of said shell at the inner surface of the front wall, the other ends of said support wires being bent to triangular shaped portions, the hypotenusal legs of each triangular portion being spaced from and substantially parallel to the upper edge of the front wall of said shell and forming necktie guiding extensions, second legs of said triangular shaped portions being in registry with one another and forming a collar button fastener receiving passage therebetween, a web connecting the lower ends of said arms to one another, knuckles on said wires adjacent their lower ends projecting into the open lower end of said

shell, and a finger extending from the central portion of said web and projecting into the open lower end of said shell, said knuckles and said fingers providing tie forming projections.

5. The combination of claim 1 wherein said projecting portion constitutes knuckles on the lower ends of said arms, said knuckles preventing spaced portions of a necktie from contacting the inner lower edge surface of said arcuate front wall.
- 10 5. The combination of claim 1 wherein said projecting portion constitutes a knuckle on said web, said knuckle preventing a central portion of a necktie passing through the shell from contacting the inner lower edge surface of said arcuate front wall.
